UNITED STATES PATENT OFFICE.

ROBERT A. CUMMINGS, OF BEAVER, PENNSYLVANIA.

REINFORCED-CONCRETE SLAB.

1,035,323.

Specification of Letters Patent. Patented Aug. 13, 1912.

Application filed June 11, 1909. Serial No. 501,630.

To all whom it may concern:

Be it known that I, ROBERT A. CUMMINGS, a resident of Beaver, in the county of Beaver and State of Pennsylvania, have 5 invented a new and useful Improvement in Reinforced-Concrete Slabs, of which the following is a specification.

This invention relates to reinforcement for concrete slabs, such as floor or ceiling 10 constructions for buildings, viaducts and the like, and roofs or covers for buildings, vaults, sidewalks and the like.

The object of the invention is to provide 15 a reinforcement for such concrete structures which will take care of either tension or compression stresses in both surfaces of the slab, and thereby prevent such slabs from cracking or failing no matter how supported, whether merely at the ends or edges or 20 at one or any greater number of intermediate points.

In the construction of reinforced concrete 25 floors, roofs and all similar structures where the concrete forms a broad thin body, which 30 can be termed a slab, it has been the practice to put the metal reinforcement practically entirely in one face of the structure, generally in or near the lower face, to take 35 care of the tension stresses which exist in the lower surface of the slab when loaded between the supports. In many such structures the 40 slabs have cracked on their upper surfaces in adjoining panels over the beams or other members upon which the slab is supported. I 45 have discovered that this failure of the slab as ordinarily constructed is due to a lack of 50 intimate connection of the main tension members with the parts in compression and especially at points of contra-flexure in 55 slabs supported as floor sections or the like, in which the main tension members do not 60 always cross each other parallel with the supports, but are at about 45 degrees with the supports in order to intersect the diagonal 65 tension cracks that develop when loaded to destruction.

The present invention has for its object 70 to overcome this difficulty and to provide a reinforcement system which absolutely prevents such cracking and which adapts itself to any size of slab and entirely irrespective 75 of the relative location or number of points at which the slab is supported.

The invention consists, generally stated, 80 in providing a reinforcement for slabs, preferably in the form of a unit or unitary

structure, and which will equally take care of either tension or compression stresses in both sides of the slab or like structure.

In the accompanying drawings Figure 1 60 is a vertical section through a slab having therein the simplest form of my reinforcement; Fig. 2 is a similar view illustrating a modification; Fig. 3 is a similar view showing the construction of Fig. 1 with the 65 addition of straight transverse members at the bottom; Fig. 4 is a similar view showing my reinforcement in a more complete 70 form; Fig. 5 is a plan view of the reinforcement shown in Fig. 4; Fig. 6 is a vertical 75 section showing another modification; and Figs. 7, 8 and 9 are detail views of portions of the structure.

In the drawings the numeral 1 indicates 80 the body of the concrete slab, which may be 85 a floor, ceiling, roof or other portion of a building, viaduct, vault or the like. The reinforcement in its simplest form, shown 90 in Fig. 1, embodies a series of main reinforcement members or rods 2 which are located in the lower portion of the slab, near its lower surface, and which for brevity of description are termed longitudinal tension members, although as a matter of fact the slab may be shorter in the direction in 95 which these members extend than in the direction at right angles thereto. Connecting these main or longitudinal members 2 are a series of secondary members 3 which I 100 will term transverse members, which between the members 2 are bent upwardly as shown to form zig zag strips and loops 4 extending up into proximity to the top surface of the slab, and which become embedded in the concrete and tie the tension members 2 to a body of concrete which is in compression. The zig zag members 3 may be 105 in planes at right angles to the planes of the main tension members or at an angle thereto. This form of reinforcement is particularly adapted to such slabs as are supported at their edges, and in which the lower surfaces are in tension. The rods 2 in this case take care of the tension stresses while the loops 4 extend up into the compression zone of the slab.

Fig. 2 shows a modification in which, in addition to the members just described, there are provided a series of top longitudinal members or rods 5 secured in or to 110 the upper angles of the zigzag members 3. This form of reinforcement will take care

of either tension or compression stresses in either the top or bottom surface equally well.

Fig. 3 shows the same structure as shown in Fig. 1 with the addition of a series of straight transverse members 6 secured to the longitudinal members 2, and which serve to hold the looped structure of Fig. 1 from flattening out.

Figs. 4 and 5 show a more complete form in which the longitudinal members 2 and 5, both at top and bottom are employed with the zigzag members 3 united alternately to the top and bottom longitudinal members, together with the straight transverse members 6 at the bottom and similar members 7 at the top. Preferably the straight transverse members 6 and 7 will be of less number than the zigzag members 3, as shown in Fig. 5. The top member 7 may be placed directly over a zigzag member, but the bottom members 6 are shown intermediate adjacent zigzag members. This form of reinforcement will take care of either tension or compression stresses in either surface of the slab, and if all the parts are of equal strength will take care of these stresses uniformly in the two surfaces. It can, of course, be varied to take care of greater stress in one surface than in the other by simply making the top or bottom series of longitudinal members heavier than the other series.

If desired, the transverse zigzag members may be arranged as shown in Fig. 6 where each alternate one of the longitudinal members in the same plane is connected to one zigzag transverse member, while the remaining longitudinal members in the same plane are connected to another zigzag member, as will be readily apparent from the drawings.

In all forms of the reinforcement the several longitudinal and transverse members are connected so as to form practically a unitary reinforcement structure which can be placed in position in the molds or on the centering by unskilled labor and the concrete then filled in, and which will insure the proper distribution of the metal in the concrete. The connection of the transverse and longitudinal members may be effected in various ways, either by welding at the points where the transverse members cross the longitudinal members, or in some other mechanical manner suitably securing the parts together. I prefer to make the union by welding, as this can be economically and quickly effected by the electric welding process and gives a firm union. This is shown at 9, Fig. 9, and is the intended manner of connecting these parts shown in Figs. 1 to 6. Instead of welding, however, the parts can be suitably tied together in any suitable way, or they may be united as shown in Fig. 7 by cutting a tongue 10 out

of the transverse member and bending the same partly around the longitudinal member. Various other forms of uniting these parts may be devised.

Preferably the main or longitudinal members 2 and 5 will be suitable round or de-formed bars, while the transverse members may be and preferably are in the form of flat strips or bands of metal which can be more easily united to the longitudinal members than if they were round. However, the cross-sectional shape of the members is unimportant and they can be made of any desired shape and size. The longitudinal members are of materially greater cross-sectional size than the transverse members.

To assist in properly positioning the reinforcement unit I provide suitable means for spacing said reinforcement from the centering. This is shown in the form of projecting fingers 11 cut from the transverse members and bent outwardly at the lower portion of the reinforcement so as to form supports to rest upon the centering and hold the reinforcement the proper distance above the latter.

The form of reinforcement shown in Figs. 1 and 2 may be made by taking metal mesh of any kind of the proper size and corrugating the same. The spaces between the longitudinal members may be varied to meet special conditions. Where the load is rather light these members will be spaced considerable distances apart and the zigzag or looped transverse members will therefore form corresponding large angles, while where greater stresses are to be taken care of the longitudinal members will be placed close together and the transverse zigzag or looped members will have correspondingly smaller angles.

As above stated the members forming the reinforcement are so united as to form practically a unit which is placed as such before filling in the concrete. This holds the several members of the reinforcement in their proper relative positions and insures the proper distribution of the metal in the structure and enables the work of putting in place and filling in the concrete to be performed by comparatively unskilled labor. With reinforcement of the character described the slab or floor construction can be supported in any desired manner, either at its ends or edges, or at any desired number of points between the ends or edges. In fact the supports for the slab may be variously located since the reinforcement takes care of either compression or tension stresses equally well in both surfaces of the slab. The portions between the supports of course are in tension in their lower faces and in compression in their upper faces, while the portions over the supports are in tension in their upper

faces and in compression in their lower faces, and there are also points of contraflexure where the stress over the supports merge into those between the supports. The 5 reinforcement described, however, effectually takes care of all these stresses and therefore the floor or other structure containing the reinforcement will not crack by reversals of stress in adjoining panels over the supports 10 or between the same.

What I claim is:

1. A reinforcement structure for concrete slabs comprising two series of three or more straight longitudinal bars, the bars of the 15 two series lying in different planes with a clear space therebetween, a series of transverse zigzag shaped bars extending at right angles to the longitudinal bars and lying at close intervals in vertical planes and firmly 20 united at their angles to the two series of longitudinal bars, and a series of straight transverse bars extending at right angles to one series of longitudinal bars and firmly 25 united thereto and out of contact with the other series of straight bars.

2. A reinforcement structure for concrete slabs comprising two series of three or more straight longitudinal bars, the bars of the 30 two series lying in different planes, a series of transverse zigzag shaped bars extending at right angles to the longitudinal bars and lying at close intervals in vertical planes and

firmly united at their angles to the longitudinal bars, and a series of straight transverse bars arranged at right angles to each 35 series of longitudinal bars and firmly united thereto, the straight transverse bars of each of the series being out of contact with and spaced from the longitudinal bars of the other series.

3. A reinforcement structure for concrete slabs comprising a series of straight longitudinal rods lying in the same plane, a series of transverse bars arranged at close intervals and extending at right angles to 45 the longitudinal rods and intermediate the latter being formed into loops projecting toward the opposite side of the slab, the loops of any one of said transverse bars lying in a common plane transverse to the 50 longitudinal rods, and a third series of bars extending at right angles to the longitudinal rods and extending in a straight line between said rods, both series of transverse bars being immovably secured to the longitudinal rods independently of the bars of the other transverse series.

In testimony whereof, I have hereunto set my hand.

ROBERT A. CUMMINGS.
